UNITED STATES PATENT OFFICE.

JOHN EDWIN KILBURN, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

CAR-SEAT.

1,188,456.

Specification of Letters Patent. Patented June 27, 1916.

Application filed July 16, 1912. Serial No. 709,642.

To all whom it may concern:

Be it known that I, JOHN E. KILBURN, a citizen of the United States, residing at Philadelphia, in the county of Philadelphia and State of Pennsylvania, have invented 5 certain new and useful Improvements in Car-Seats, (Case A,) of which the following is a specification.

This invention relates to car-seats and 10 more particularly to seats of the non-reversible type in which the back is stationarily mounted at the rear edge of the seat-cushion.

The primary object of the invention is to 15 provide an improved form of support for the cushions of a car-seat of this type which is of light weight and at the same time possesses the requisite degree of strength.

Further objects of the invention are to 20 provide a seat-support which may be manufactured at low cost, which is of attractive appearance and which permits of using cushions, and particularly a seat-cushion, which are of the maximum length.

25 One feature of the invention involves the provision of a seat-support which is a combined seat-end and back-supporting arm, these two parts being formed from a single piece of sheet-metal. Such a single piece 30 seat-end and arm may be formed integral with a suitable base-portion or a separate pedestal may be provided on which the combined seat-end and arm are mounted.

The invention further involves the provision of a supporting structure for the 35 cushions of a car-seat consisting of a horizontally-disposed member for supporting the seat-cushion, an arm for supporting the back-cushion and an off-set between these 40 two parts whereby the back-supporting arm is displaced from the plane of the seat-end in the direction of the length of the seat. In this way it is possible to have the back-supporting arm secured to the end of the 45 back-cushion and at the same time to have the end of the seat-cushion extend beyond the end of the back-cushion whereby the seat-cushion is made of the maximum length to give the greatest amount of seating surface and the back-cushion is made of 50 slightly less length so that the aisle adjacent to the end of the seat will be of greater width above the seat-cushions where such greater width is desired. In a standard of 55 this character for supporting the seat-and

back-cushions of a car-seat, the standard is subjected to the greatest strain at the angle therein where the horizontal and upright members of the standard join and it is essential that it be of small size at this point so 60 as not to encroach upon the space directly in rear of the seat. For this reason a standard constructed in accordance with the invention is provided with a reinforce at the angle therein which reinforce extends over 65 the offset in the standard and overlaps the adjacent ends of the back-supporting arm and the member which supports the seat-cushion. This reinforce is united to the standard preferably by welding so that 70 along the offset in the standard, the latter is of box-section and hence of great strength.

The reinforced offset between the supports for the seat- and back-cushions above referred to may be, and preferably is, employed in the form of a seat-support wherein in the seat-end and the back-supporting arm are combined as in such a structure the advantages of both features of the present invention are obtained.

The preferred embodiment of the invention is illustrated in the accompanying drawings in which—

Figure 1 is a front view of a car-seat broken away and sectioned in part, Fig. 2 85 is an end view of the seat, Fig. 3 is a view of the inner side of the combined seat-end and back-supporting arm, Fig. 4 is a sectional view on line 4—4 of Fig. 7, Figs. 5 and 6 are sectional views on lines 5—5 and 90 6—6, respectively, of Fig. 3, Fig. 7 is a rear view of the standard shown in Fig. 3, Fig. 8 is a section on line 8—8 of Fig. 3, Fig. 9 is a front view of a modified form of seat, Fig. 10 is a view of the standard employed in the seat shown in Fig. 9 and Fig. 11 is a section on line 11—11 of Fig. 10.

Referring first to Figs. 1 to 8 inclusive, the seat illustrated consists of a back-cushion 12 and a seat-cushion 13 supported on suitable sheet-metal pedestals 14. In the drawing two such pedestals 14 and seat-supports constructed as hereinafter described are employed at the two ends of the seat but it will be understood that the construction illustrated may be employed at one end only, the other end being supported upon the wall of the car. The supporting structure includes a combined seat-end and back-supporting arm as shown in Figs. 3 to 110

8 inclusive. This supporting structure is formed from a single piece of sheet-metal shaped to provide a horizontally-disposed portion 15 which constitutes the seat-end 5 and an upwardly extending back-supporting arm 16. The piece of sheet-metal, after being cut to the proper configuration, is pressed to the desired form, preferably, that indicated in the drawing. The shaping of 10 the sheet-metal piece includes the provision of an offset 17 therein so that the arm 16 is displaced from the plane of the seat-end 15 in the direction of the length of the seat. The cross-sectional shape of the back-supporting arm 16 is preferably that shown in 15 Fig. 5 from which it will be seen that an integral flange 18 is provided upon the arm 16 which flange is adapted to bear against the rear face of the back-cushion when the 20 arm proper is secured to the ends of the back-cushion.

The horizontally-disposed portion 15 of the seat-support which constitutes the seat-end, is provided with an inwardly-turned 25 flange 19 along the upper and lower edges thereof and along the front edge. The combined seat-end and back-supporting arm thus constructed is strengthened at the angle 30 therein where it is subjected to the greatest strain. This is done by providing a reinforce 35 at the angle which reinforce extends over the offset 17 and the adjacent ends of the seat-end and back-arm. This reinforce is shown at 20. A piece of sheet-metal is bent in the direction of its length as required 40 by the offset 17, preferably in the manner shown in Fig. 8. When the piece 20 is thus shaped it is secured to the flanges at the edges of the combined seat-end and back-arm 45 preferably by welding so that the structure is made of box-section throughout the offset therein and the parts adjacent to the offset. As shown in Fig. 3 the reinforce is extended up within the back-supporting 50 arm 16 a short distance so as to insure that it will be firmly secured to the back-supporting arm.

The seat-end portion of the seat-support is 55 preferably stiffened by the application to the inner side thereof of a sheet-metal plate. This plate is shown at 21. Over most of its surface it is spaced apart from the body-portion of the seat-end 15 but its edges 22 are shaped down so as to lie against the inner 60 side of the seat-end 15. These edges 22 are welded to the seat-end.

The combined seat-end and back-supporting arm thus constructed is secured to the 65 ends of connecting rails 23. For this purpose end-pieces 24 are riveted to the ends of the connecting rails 23 and bolts 25 passed through these end pieces and openings provided therefor in the seat-end. When the 70 nuts on the inner ends of these bolts 25 are tightened up, the combined seat-end and

back-supporting arm is rigidly secured to the connecting rails 22. Both of the end-pieces 24 have inclined upper surfaces as shown in Fig. 3, but the forward end piece is of greater height than the rear one and 70 is provided with a pin 26 upon its upper face. The seat-cushion 13 is mounted upon these end pieces 24, it being held in position by the pin 26 which enters an opening in its frame. The size of the end-pieces 24 is such 75 that the cushion will be maintained at the proper inclination. The back-cushion 12 has its end secured to the back-supporting arm 16 with the rear face of the cushion bearing against the flange 18. 80

By this construction it will be seen that the seat is provided with a seat-end, that this seat-end and the back-supporting arm are formed integral and that by reason of the offset in this integral seat-support the seat-cushion may be made longer than the back-cushion. This is desirable as it is important to make the seat-cushion of the maximum length in order to give large seating surface and the seat-cushion may be made longer 90 than the back-cushion as the aisle at the end of the seat may be narrower on a level with the seat-cushion than it is above those cushions. By forming the offset back-supporting arm and seat-end from a single piece of 95 sheet-metal and reinforcing the structure over the offset and the angle at the joint between the arm and seat-end, the requisite amount of strength is provided and yet the structure may be made of such small dimensions that it will not obstruct free entrance 100 to the space immediately in rear of the seat.

In Figs. 9, 10 and 11, a somewhat similar construction is employed differing from that shown in the preceding figures in the respect 105 that the horizontally-disposed portion of the seat-support is not a seat-end; instead, this horizontally-disposed portion extends under the seat-cushion and supports the latter upon its upper face. Referring to these 110 figures, the standard consists of a horizontally-disposed portion 26 and a back-supporting arm 27 formed from a single piece of sheet-metal, there being an offset 28 between them so that the arm 27 is displaced 115 from the plane of the member 26. A reinforce 29 is provided at the angle where the arm 27 and member 26 are joined. This reinforce 29 is a sheet-metal strip bent to follow the shape of the offset and secured 120 at its edges to flanges provided on the edges of the offset 28 and member 26. It is not essential that reinforce 29 be extended upwardly into the arm 27, though it may be if desired; in any case the reinforce 29 will 125 extend along the offset and around the angle in the standard. The horizontally-disposed member of the standard has flanges 30 at its upper, lower and front edges and a pin 31 is mounted upon the upper flange 30. 130

Gussets 32 are preferably provided for pressing the flanges 30.

The standard shown in Fig. 10 is mounted upon a pedestal 33 of any suitable construction and a seat-cushion is supported upon the flange 30 at the upper edge of the horizontally-disposed arm 26 of the standard with the pin 31 entering an opening in the seat-cushion. The back-cushion has its end secured to the back-supporting arm 27 with the rear face of the cushion bearing against the flange formed on the rear edge of arm 27.

In the constructions above described, the body of the standard is formed from a single piece of sheet-metal, this piece forming both the horizontally-disposed portion and the upwardly-extending arm of the standard. But in some cases, as when the offset is very small, two sheet-metal pieces may be employed, these being welded together so that they are in effect a single piece. I wish it understood, therefore, that this latter construction is included within the scope of the appended claims.

Having described my invention, what I claim as new therein and desire to secure by Letters Patent of the United States is:

1. In a car-seat, a support formed of sheet-metal and comprising a horizontally disposed flanged, cushion-supporting member, an upwardly extending flanged, back-supporting arm offset from said member so as to lie in a plane displaced in the direction of the length of the seat from the plane of said member and an offset portion connecting the arm and member and integral with both of them, a sheet-metal reinforce for said combined arm and member extending throughout said offset portion, and secured to the flanges of said member and arm so that the complete offset portion is of box-section, a back-cushion having its end secured to said arm, and a seat-cushion of greater length than the back-cushion mounted upon said member, substantially as set forth.

2. In a car-seat, a combined seat-end and back-supporting arm formed from a single piece of sheet-metal and having an offset therein whereby the arm is displaced from the seat-end in the direction of the length of the seat, a sheet-metal reinforce applied to

said piece and making the same of box-section throughout said offset and at the adjacent ends of the arm and seat-end, a back-cushion having its end secured to said back-supporting arm, and a seat-cushion of greater length than the back-cushion supported in position with its end closely adjacent to said seat-end, substantially as set forth.

3. In a car-seat, a combined seat-end and back-supporting arm formed from a single piece of sheet-metal, pressed to shape, the seat-end portion thereof having lateral flanges and the back-supporting arm portion being adapted to contact the end of a back-cushion, and having a flange adapted to contact the rear surface of the back-cushion, the said piece having an offset therein whereby the arm is displaced from the seat-end in the direction of the end of the seat, a stiffening plate having flanged edges lying substantially parallel to said seat-end portion, and secured, at its said edges, to the inner face of said seat-end portion, and a reinforcing member of sheet-metal applied to said seat-end and arm at the offset portion thereof, bent to conform to the shape of said offset, and secured to said flanges at the edges of said seat-end portion and back-supporting arm portion, substantially as set forth.

4. In a car-seat, the combination of a pedestal, a cross-rail secured thereon, a standard comprising a seat-end portion secured to the end of the cross-rail and a back-supporting arm offset from said portion in the direction of the length of said cross-rail, said portion and arm being of flanged pressed metal, and a reinforcing plate applied to said seat-end portion and arm at the offset portion thereof, bent to conform to the shape of said offset, and secured to the flanges of said seat-end portion and back-supporting arm portion, substantially as set forth.

This specification signed and witnessed this 5th day of July, 1912.

JOHN EDWIN KILBURN.
